US00D579014S

(12) **United States Design Patent**
Travers et al.

(10) **Patent No.:** **US D579,014 S**
(45) **Date of Patent:** **** Oct. 21, 2008**

(54) **PERSONAL VIDEO DISPLAY DEVICE**

(75) Inventors: **Paul Travers**, Honeoye Falls, NY (US);
Vincent J. Ferrer, Rochester, NY (US);
Paul Klock, Rochester, NY (US); **Ian Sinclair**, Indian Falls, NY (US)

(73) Assignee: **Vuxiz Corporation**, Rochester, NY (US)

(**) Term: **14 Years**

(21) Appl. No.: **29/278,600**

(22) Filed: **Apr. 3, 2007**

(51) **LOC (8) Cl.** **14-02**

(52) **U.S. Cl.** **D14/372**

(58) **Field of Classification Search** **D14/372,**

(57) **CLAIM**

The ornamental design for the personal video display device, as shown and described herein.

DESCRIPTION

FIG. 1 is a perspective view of the personal video display device according to a preferred embodiment of the invention.

FIG. 2 is a top view of the personal video display device of FIG. 1.

FIG. 3 is a bottom view of the personal video display device of FIG. 1.

FIG. 4 is a front view of the personal video display device of FIG. 1.

FIG. 5 is a rear view of the personal video display device of FIG. 1.

FIG. 6 is a right-side view of the personal video display device of FIG. 1; and,

FIG. 7 is a left-side view of the personal video display device of FIG. 1.

The portions of the personal video display device, shown in broken lines form no part of the claimed design.
